ATTORNEY.

UNITED STATES PATENT OFFICE.

FRANK G. CALDWELL, OF WHEELING, WEST VIRGINIA.

DESIGN FOR A CLAMP FOR SHEET-METAL ROOFING-PLATES.

SPECIFICATION forming part of Design No. 31,086, dated June 27, 1899.

Application filed May 31, 1899. Serial No. 718,924. Term of patent 14 years.

To all whom it may concern:

Be it known that I, FRANK G. CALDWELL, a citizen of the United States, residing at Wheeling, in the county of Ohio and State of

5 West Virginia, have invented a new and original Design for Clamps for Sheet-Metal Roofing-Plates, of which the following is a specification.

10 The leading and characteristic feature of my design is the clamp made the subject of the illustration herein, in which the figure of the drawing represents a perspective view.

15 Said clamp is made from a strip having parallel side edges bent to form a flat base 1, a flange 2 at one end of the base, extending upwardly and inwardly therefrom and forming

an acute angle therewith, and a lip or extension 3 on the flange 2, which extends upwardly and outwardly therefrom and lies at an acute angle thereto. 20

What I claim is—

The design for a clamp for sheet-metal roofing-plates, substantially as shown and described.

In testimony whereof I have hereunto set my hand in presence of two subscribing witnesses.

FRANK G. CALDWELL.
